UNITED STATES PATENT OFFICE.

WILLIAM J. TURNER, OF PROVIDENCE, RHODE ISLAND.

REGULATOR.

1,296,881.

Specification of Letters Patent. Patented Mar. 11, 1919.

Application filed April 6, 1916. Serial No. 89,359.

To all whom it may concern:

Be it known that I, WILLIAM J. TURNER, a citizen of the United States, residing at Providence, in the county of Providence and 5 State of Rhode Island, have invented new and useful Improvements in Regulators, of which the following is a specification.

This invention relates to improvements in regulators. More particularly it relates to 10 means for making any regulation, such as the opening or closing of a valve, required when the level of liquid in a principal container has changed. It is illustrated as it 15 may be applied in regulating the supply of feed water to a boiler where it is desired to keep the level of water within the boiler approximately uniform. It may however, be used for other purposes, as for example to regulate the dampers that control the fire 20 under a boiler in a vapor or partial vacuum system of steam heating. In such a case the level of water within the boiler varies with the pressure of steam therein, and the regulating devices of the invention may be applied 25 to alter the setting of the dampers when the pressure of steam has changed the water level. Adaptations of the invention to such an organization are illustrated and 30 claimed more in detail in my applications for Letters Patent Serial Nos. 89,358 and 89,360. The invention is by no means limited to use in the connections thus shown.

The invention provides a movable receiver 35 outside of but connected to the liquid space of the principal container, in free communication therewith and capable of holding the liquid in varying quantities, and supported on balancing means, such as a lever, such that the balance swings according as the 40 weight of liquid in the receiver is greater or less than a predetermined amount. In swinging it operates the desired mechanism, such as a valve, in the proper direction, and without losing its communication with the 45 principal container sets itself in position to be moved oppositely when a sufficient change to the opposite has occurred therein. Further features of the invention relate to the means of supporting of such a receiver, and 50 of keeping the whole in stability and of holding it by a single bolt; also to the means for supporting it thus movably with respect to the main liquid container in an inexpensive way, as by providing parallelogram arrangement of stiff and flexible passages. Another 55 feature is to provide so that it can be made

and shipped from a central factory in form for an ordinary workman or steam fitter at the place of installation to set it in proper conformity to the particular local conditions 60 as to height of studding, level of water in boiler, etc., without error and without special supervision of the setting, with the result that the appliance can be used in connection with boilers or other liquid containers of any 65 make and at any place, with proper supports cheaply made of locally obtained materials.

Another feature of the invention is the combination of such a receiver with a steam boiler working on a closed pressure system in 70 which a circuit, including the water part of the boiler, receiver, and the steam part of the boiler, is a feature, so that the water in the receiver registers with the water level in the boiler and automatically provides for the 75 opening or closing of the valve admitting feed water to the boiler in order to keep the water level approximately constant and always safe in the boiler. And in this connection another feature provides for sure operation 80 and positive control of the valve, automatically exaggerating or emphasizing its action.

It is intended by suitable expression in the appended claims to cover whatever features 85 of patentable novelty exist in the invention disclosed. The invention may be embodied in various means and applied in connection with apparatus of various types. In the accompanying drawings:

Figure 1 illustrates in side elevation an application of the invention as a regulator for feed water for a steam boiler;

Fig. 2 is a side elevation of the receiver in section on the line 2—2 of Fig. 1, enlarged;

Fig. 3 is a plan of the same in section on the line 3—3 of Fig. 2;

Fig. 4 is a side elevation, enlarged and in medial section, of a detail of Fig. 1; and

Fig. 5 is a side elevation of the same, in 100 section on the line 5—5 of Fig. 4.

Referring to the drawings, 10 indicates a steam boiler, 11 the water inlet thereto, 12 the dome or steam space, and 13 indicates the water level. A standard built in sections of iron piping 14, has intervening fittings 15, 16 and 23, the middle one of which fulcrums a lever 17. On one arm of this is hung the receiver 18, and on the other arm is an adjustable weight 19. A pipe 20 connects 110 the water space of the boiler with fitting 15 whence a flexible connection 21 continues to

the lower part of receiver 18. The receiver is preferably rather long vertically. From its upper part a flexible connection 22 leads to fitting 23 and thence pipe 24 affords connection with the steam space 12 of the boiler. There is therefore, an uninterrupted circuit from the water space of the boiler through the receiver 18 to the steam space of the boiler so that the water in the receiver will 10 always stand at the same level 13 as the water in the boiler, varying with it.

Although thus connected, the weight of water in the receiver is sustained by the column or standard 14. One feature of the invention relates to the manner in which this column is constructed and the receiver supported movably thereon, in order to provide stability and lightness coupled with the necessary strength and adaptability to the surroundings of its installation, which, in practice, vary greatly as to relative levels of floor, of ceiling and of water in the boiler. As illustrated, the receiver depends from a single bolt 25 which, acting as a pivot, passes 20 through one of the various holes provided in the simple bar lever 17; and that lever in turn is supported at its fulcrum by a single pivot bolt 26 passing through the fitting 16. In view of the varying water level in it, it is 30 desirable that the receiver hang vertically from its pivot. It also should be symmetrically disposed with respect thereto, as a tendency to tip to either side would produce increased friction and decreased sensitivity of action. Moreover, a simple suspension will not serve, for the space at the top of the receiver is hampered with a connection which ultimately leads to the boiler, or, in 35 one of the other forms by a vent with a wide diaphragm controlling it, and these ought to be in the middle in order that the desired balance may be had. The bottom is likewise hampered by a connection which ultimately leads to the boiler. The invention provides 40 means by which the lever 17 passes through the metal which constitutes the receiver 18, between these connections but on the medial line near the top. Preferably the tank is of vertically elongated form, so that there is a 45 considerable distance through which the level of water may rise or fall; and this level of water may even extend above the place where the pivotal support 25 is, but the receiver always hangs in stable position, notwithstanding the changes of level of water 50 therein and notwithstanding that the water is sometimes above the level of that support, because the center of the gravity of the receiver even when filled with water is below 55 the bolt 25. To accomplish this the shell that constitutes the receiver is formed with two intersecting central passages from exterior to exterior, through one of which the lever may be put, and through the other of 60 which the supporting pin 25 passes, penetrat-

ing both shell and lever but not penetrating the interior of the shell. This is accomplished by providing deep recesses on opposite sides of the shell, so deep that they meet at the center, in the provision made for the lever; and so deep in the provision made for the bolt, that there is only a web of metal, but no water space, intervening between each and the lever space, which web receives the bolt 25 and supports the whole shell. 75

Within the shell, the angular spaces between the deep indentations made by these recesses provide passages through which the water can rise and fall. The hole through which the lever goes has diverging walls 80 above and below, from the center outward, so that the receiver can remain vertically swinging on its pivotal support 25, notwithstanding the tipping of the lever 17. A number of holes may be provided in the lever 85 at differing distances from its fulcrum so that the receiver can be set under different conditions of leverage. On the other arm of the lever there may also be holes at different distances, and a hook on which as many 90 weights as desired may be placed in order to provide the desired balance for the tank. The fitting 16 in the upright tubular column 14 is pierced by a hole extending horizontally, through which the lever passes, and by 95 another horizontally at right angles to the lever hole, in which other is put the fulcrum bolt 26. This fitting has bosses at top and bottom with which sections of iron piping connect. The fitting 15 for the water passage through the standard and the fitting 23 for the steam passage through the standard have similar bosses at top and bottom into which the lengths of iron pipe may be 100 screwed. As iron piping is a commodity at hand in every community, the invention as thus described affords a convenient means by which a single factory can supply the trade with these columns, in such form that the apparatus can be set at any desired level 105 with respect to floor or ceiling, so as to make the tank at a proper elevation with respect to the normal water level within the boiler or other container for liquid with respect to which the apparatus is to be used, without 110 the burden of carrying a stock of assorted sizes of different lengths, and of different elevations for each length. The factory can furnish the parts 15 and 16 with a suitable length 14 between them, assembled properly 115 at the factory, either in separate pieces as illustrated in Fig. 4 or with the parts 14, 15 and 16 integral. It is only necessary for the workman to determine his desired level for the fulcrum bolt, with reference to boiler 120 water level, pursuant to instructions. Then the distances from floor to bottom of fitting 15, and from ceiling to top of fitting 16 determine lengths of iron pipe to be cut for the parts 14' which constitute merely tubu- 130

lar extensions of the column 14, reaching to shoes 40 supplied by the factory for engagement with the floor and ceiling respectively. These shoes have bosses with threads 5 long enough to receive a considerable length of pipe, enough in fact to permit of the installation of the column between floor and ceiling after the bosses have been screwed upon the pipe sections 14, and this pipe may 10 be, if desired, oppositely threaded at its ends. Once in place, the bosses can be screwed out against until the entire column including extensions has become a tight stanchion, fixed thus by set screws, and floor 15 and ceiling screws.

From the lever 17 is a connection to a valve 31 controlling the supply of feed water to the boiler, or to whatever else is to be operated or regulated. In the form illustrated 20 sufficient weight is to be placed at 19 to not quite balance the weight of the receiver, the connected parts and the water in it, when the feed water is above normal level. The connection to the said feed water valve 25 31 is arranged so that that valve is then closed but would be opened by a descent of the weights 19. The action is then very simple. Whenever the level of water in the boiler becomes lower than the normal level, 30 there is a less weight of water to be supported by the lever. Upon this becoming sufficiently less, it is over balanced by the weights 19, and the weights descend and the receiver rises and in so doing the said water 35 valve 31 is pulled open by the lever 17. Upon such rising the level of water in the receiver becomes relatively lower, owing to the rise of the receiver shell, and the weight of water supported thereby becomes less, so 40 that there is an enhanced preponderance of the weights 19. When sufficient water has entered the boiler so that the level in the receiver 17, corresponding to the level in the boiler, has risen high enough for the receiver to over balance the weights, the receiver descends, thus shutting the said water 45 valve. On account of the movement of receiver and the differential between the level at which water operates it to open the said 50 valve and that at which water operates it to close the said valve, it is manifest that a substantial addition to the water in the boiler is made each time the apparatus operates. The amount of water thus introduced 55 at each operation of the regulator may be varied by varying the vertical travel of receiver, and this obviously may be done by fixing the limiting stops 33 or by setting the receiver at a different distance from the 60 standard which supports it. When the receiver swings down, owing to over balancing by weight of water therein, the overbalancing becomes greater as it descends because the depth of water within it increases 65 with the descent of its bottom, and more

water enters it in order to equal its former level, all of which is supported on its end of the lever. Hence operation in the opposite direction to raise the receiver, swing the lever oppositely and open the valve again, 70 will not occur until there has been a material lowering of water level in the boiler, sufficient to exhaust the extra amount of said water that was thus admitted when the receiver sank. This amount, being determined 75 by the vertical movement of the receiver can be regulated at will by setting the receiver's distance from the fulcrum of lever 17, and adjusting weights 19 accordingly, or by setting the stops that limit the swing of lever 80 17. The fact that this differentiation between the point at which the receiver will be swung down, and that at which it will be swung up can be made to correspond to a considerable difference of level of water in 85 the receiver enables the apparatus to be used also for regulating the water supply to a partial vacuum or a vapor system of steam heating, in which systems the water level varies more or less with variation of pressure 90 in the boiler, one part of the system being open to atmosphere while another part may be subject to a slight vacuum or slight pressure. The said feed water regulator may be made with so great a differential be- 95 tween its limiting positions, and of sufficiently large area in cross section horizontally, so that the fluctuations of water level due to this variation of steam pressure do not affect it materially, and so that it is af- 100 fected only by the more fundamental changes of water level resulting from presence or absence of a sufficient body of water, which determines the general zone in which the pressure changes of steam will be effec- 105 tive.

If the regulating receiver be used to adjust the position of dampers, for regulating the fire in a steam "vapor" heating system the top of the receiver may be open to the 110 atmosphere instead of being connected to the steam part of the boiler as represented by passage 22, 23 and 24. In that case the changes of elevation of water in the receiver will depend mainly upon the 115 changes in pressure in the boiler, and the level of water in the receiver will not correspond with the level in the boiler, but will rise, for example, when the level in the boiler is depressed by rise of steam pressure 120 therein. This rise of water in the regulative receiver adds to its weight so that it presently swings downward thus operating its connections with dampers for regulating the fire; and when it has thus once operated the 125 differential above explained keeps it so until the pressure of steam has for any reason fallen sufficiently so that the differential of weight resulting from the change of position of the receiver has been made up. In the 130

meantime any changes of quantity of water in the boiler, such as would require the injection of more feed water, make relatively little difference in the water in the regulatory receiver, but in so far as the addition of 5 fresh feed water cools the body of water already in the boiler, and thus reduces the rate of making steam, this diminishes the steam pressure and thus influences the regulator to open the drafts and increase the 10 fire in order to neutralize the effect of the cool feed water that has entered.

Another feature of the invention relates 15 to the mounting of the receiver with flexible connections at both ends. The flexible connections are approximately horizontal and are spaced equidistantly on a rigid vertical base line and on the receiver. This produces a sort of parallelogram having one 20 vertical side fixed, being the part of the standard 14 from the fitting 15, where the water passage is flexibly connected, to the fitting 16, where the lever is fulcrumed, or to the fitting 23 where the upper flexible 25 connection is joined to the steam passage, and having a vertical side, movable, consisting of the receiver. As the length of each of the flexible connections, which may be of any suitable kind of flexible tubing, is 30 equal substantially to the length of the lever 17 between its fulcrum at 26 and its pivotal connection to the receiver at 25, only a minimum of flexible tubing is required. Indeed, if suitably packed swinging joints 35 were provided, stiff tubing might be substituted for the flexible tubing, which would swing always in parallelism with the lever 17. This is an improvement over an arrangement which might be made, by running the flexible tubing from the bottom 40 of the receiver directly downward to the supply pipe under it, in which case the whole vertical travel of the receiver would have to be taken up by bends in the flexible tubing, whereas by leading the tubing 45 approximately horizontally as illustrated, there is a minimum of bending, and therefore minimum of wear, and a maximum of life for the tubing, as well as minimum of 50 expense because less is needed.

By the described construction it will be seen that the regulatory receiver hanging from a single pivot hangs always vertically in stable equilibrium, and with abundance 55 of power to work any valve or other device required. Moreover its installation at proper level and its permanent support are effected by an exceedingly simple mechanical contrivance which cannot get out of 60 order and which can be set correctly according to local conditions by a local steam fitter with materials abundantly at hand, thus enabling a central factory to supply the trade for the whole country.

65 Although the invention is illustrated as

it may be applied to a steam heater working under pressure, for which purpose the pipe 24 provides a complete circuit, it will be understood that it might be used with a low pressure or so-called "vapor" system 70 or a "vacuum" system in which cases the return main is open to atmosphere or is connected to a suction producing means. In that case the pipe 24 might be omitted. The communication of the receiver 18 with the 75 atmosphere, and of the water return pipe of the system with the atmosphere, or with suction, gives the equivalent of the illustrated circuit through pipe 24 so that the receiver registers the water level of the boiler. 80

I claim as my invention:

1. In combination, an actuating balance-lever having weight on one arm and a receiver for liquid on its other arm; and means separate from the lever adapted to connect the receiver with a container for liquid subject to fluctuations of level and to permit free flow of liquid in both directions, said receiver being penetrated by said lever, and supported thereby at a point in 90 the midst thereof but external to the walls thereof.

2. In combination, an actuating balance-lever having weight on one arm and a receiver for liquid on its other arm; and means 95 separate from the lever adapted to connect the receiver with a container for liquid subject to fluctuations of level and to permit free flow of liquid in both directions, said receiver being relatively long vertically 100 and having two intersecting horizontal passages through its upper part, not penetrating the liquid containing walls thereof, through one of which the said lever passes; and a pivot pin passing through the other 105 and through said lever.

3. In combination, an actuating balance-lever having weight on one arm and a receiver for liquid on its other arm; and means 110 separate from the lever adapted to connect the receiver with a container for liquid subject to fluctuations of level and to permit free flow of liquid in both directions, said receiver being arranged with its center of gravity below the point at which it is supported on said lever; there being a supporting column, having a portion holding at a rigid vertical distance apart the fulcrum for said lever and a fitting constituting part of the connection from the receiver to said 120 container, and having other portions consisting of separate tubular pieces attached at top and bottom thereof and thence extending respectively upward to ceiling and downward to floor.

4. In combination, an actuating balance-lever having weight on one arm and a receiver for liquid on its other arm; and means separate from the lever adapted to connect the receiver with a container for 130

liquid subject to fluctuations of level and to permit free flow of liquid in both directions, said receiver being arranged with its center of gravity below the point at 5 which it is supported on said lever; there being a supporting column, having a portion holding at a rigid vertical distance apart the fulcrum for said lever and a fitting constituting part of the connection from 10 the receiver to said container, and having other portions consisting of separate tubular pieces attached at top and bottom there-

of and thence extending respectively upward to ceiling and downward to floor; said connecting means being flexible and extending in parallelism with said lever from the receiver to the said fitting. 15

Signed by me at Boston, Massachusetts, this twenty-eighth day of March, 1916.
